(57) **CLAIM**

The ornamental design for a display screen or portion thereof with graphical user interface, as shown and described.

DESCRIPTION

The file of this patent contains at least one drawing executed in color. Copies of this patent with color drawing(s) will be provided by the Office upon request and payment of the necessary fee.

FIG. 1 is a front view of a display screen or portion thereof with graphical user interface;

FIG. 2 is a second embodiment thereof;

FIG. 3 is a third embodiment thereof;

FIG. 4 is a fourth embodiment thereof;

FIG. 5 is an alternate showing of the first embodiment;

FIG. 6 is a fifth embodiment thereof;

FIG. 7 is an alternate showing of the third embodiment;

FIG. 8 is a sixth embodiment thereof;

FIG. 9 is another alternate showing of the first embodiment;

FIG. 10 is an alternate showing of the second embodiment;

FIG. 11 is another alternate showing of the third embodiment; and,

FIG. 12 is an alternate showing of the fourth embodiment. The outer perimeter shown in broken line in the drawings illustrates a display screen or portion thereof and forms no part of the claimed design. The remaining broken lines in the drawings illustrate portions of the graphical user interface that form no part of the claimed design.
